UNITED STATES PATENT OFFICE.

GEORGE H. BENZON, JR., OF JENKINTOWN, PENNSYLVANIA, ASSIGNOR TO WILLIAM SELLERS & COMPANY, INC., OF PHILADELPHIA, PENNSYLVANIA, A CORPORATION OF PENNSYLVANIA.

PLANER.

1,380,699.

Specification of Letters Patent. Patented June 7, 1921.

Application filed June 18, 1920. Serial No. 389,812.

To all whom it may concern:

Be it known that I, GEORGE H. BENZON, Jr., a citizen of the United States, residing at Jenkintown, county of Montgomery, and 5 State of Pennsylvania, have invented a new and useful Improvement in Planers, of which the following is a full, clear, and exact description, reference being had to the accompanying drawings, which form a part 10 of this specification.

This invention relates to an improvement in automatic feeding mechanism for the cutting tool of a metal working machine, and is more particularly designed for use in connection with metal planers in which the bed to which the work is clamped is reciprocated below the tool.

The object of my invention is to provide means for maintaining the automatic feeding mechanism in timed relation to the reciprocating mechanism for the bed, if the machine is stopped between the limits of its movement, or if the automatic feed is cut out for any purpose.

25 The feeding mechanism comprises an intermittently rotated shaft, which is arranged to be actuated step by step from a suitable source, and is thrown into and out of engagement with the driving mechanism by 30 means of an escapement which is controlled electrically at the end of each movement of the table. The electric means comprises a solenoid which when energized will move the escapement lever in one direction and when deenergized will permit the escapement to be moved in a reverse direction by mechanical means, the arrangement being such that the circuit to the coil of the solenoid is closed during one stroke of the table and is broken 35 during the other stroke. I also provide a second magnet or solenoid for preventing the escapement lever from returning by gravity if the circuit to the above mentioned solenoid is broken.

40 The nature of my invention will be best understood by reference to the accompanying drawings, which will now be described, it being premised, however, that various changes may be made in the details of construction and the general arrangement of the parts, without departing from the spirit and 45 scope of my invention as defined in the appended claims.

Figure 1 of the drawings is a side eleva-

tion of a portion of a planer with a portion 55 broken away for clearness.

Fig. 2 is a diagram of an electrical controlling device embodying my invention.

Fig. 3 is a horizontal sectional view of the 60 planer showing the table drive.

Fig. 4 is a cross-sectional view of Fig. 3.

Fig. 5 is a cross-sectional view of the feed mechanism clutch and driving pulley.

Fig. 6 is an end view of the clutch shown 65 in Fig. 5.

Fig. 7 is a sectional view on the line 7—7 of Fig. 5.

Fig. 8 is a detail view of the locking mechanism on a larger scale.

In the drawings the reference character *a* 70 designates the bed of the planer on which the table *b* is adapted to reciprocate, and secured to the table is a rack *c* which meshes with a gear *d*.

The gear *d* meshes with a pinion on a gear *h* 75 connected to a shaft *e*, and *f*, *f* are fast pulleys secured to the shaft *e*, said pulleys being on opposite sides of a pair of loose pulleys *g*, *g*. *j* is a driving pulley which may be driven from any suitable source of power 80 and which is connected to the various pulleys *f*, *f*, *g*, *g* by means of a pair of belts *i*, one of which is crossed, and are arranged to actuate the train of gears before described, for reciprocating the bed. Slidably mounted 85 in suitable brackets on the frame of the machine is a belt shifter *k*, which is arranged to shift the belts *i*, to place both of said belts on the loose pulleys *g*, or one of said belts on a loose pulley and the other on a fast pulley 90 in the well known manner. Mounted in suitable bearings in projections on the frame *a* is a vertical shaft *p* and connected to the upper end of the shaft *p* is a crank *q* which is connected to the belt shifter *k*. Connected to the lower end of the shaft *p* is a second 95 crank *o* which is at right angles to the crank *q*, and connected to this crank *o* is a shifting rod *n*, the other end of which is connected to a lever *m* pivoted on the bed *a*. The upper 100 end of this lever *m* is provided with two projections out of vertical alignment with each other and which are arranged to be engaged by adjustable dogs *l*, *l'* connected to the table *b*.

Pivottally connected to the bed *a* adjacent to the lever *m* is a hand lever *r*, which is connected by means of a link *s* with the lever

105

- m*, and is adapted for shifting the mechanism by hand when it is desired to stop the machine or reverse its motion between the limits of the movement of the table *b*.
- 5   *u* is the cutting tool which is connected to the tool head *v* in any desired manner, which is movably mounted on the cross rail *x*, and along which it is adapted to be moved to shift the tool between cuts.
- 10   The cross rail *x* is adjustably mounted on suitable guides on the housing *y* and is arranged to be adjusted thereon for shifting the cross rail together with the tool head vertically with relation to the work piece to 15 be machined on the bed *b*. The tool head *v* is arranged to be adjusted or fed longitudinally along the cross rail *x*. The screw shaft or feed screw in action is actuated between cuts by ratcheting mechanism carried 20 by the gear wheel *w* on the end thereof and which mechanism is clearly disclosed in my Patent No. 911,566. The desired feeding pinion *w* is continuously in mesh with the teeth on a sector 2, which is journaled on a 25 stud shaft connected to the cross rail *x*. 3 is a crank connected to the sector 2 and which is also connected by means of a link 9 to a disk 7, the connections between the link 9 and the disk 7 being arranged to permit 30 radial adjustment in order to vary the throw of the lever 3 and consequently vary the feed of the tool. The disk 7 is also connected to a shaft mounted in a bearing on a bracket extending from the cross rail, and 35 connected to this stud shaft is a bevel gear which is in mesh with a second bevel gear 6, splined on a shaft 5. The bevel gear 6 is also carried by the cross rail *x*, so that when the cross rail is adjusted vertically, the be- 40 fore described mechanism is moved vertically on the shaft 5. This shaft is rotatably mounted in suitable bearings on the housing *y* and is arranged to be driven by bevel gears 10 from a shaft 11, which is also journaled 45 in bearings on the housing *y*. Rotatably mounted on the shaft 11 is a pulley 12 which is continuously driven from any suitable source and which is recessed for the reception of clutching mechanism as clearly 50 shown in Fig. 5. Connected to the shaft 11 is a clutch member 13, the end of which extends into a recessed portion of the pulley 12, and is provided with cam surfaces 32 as clearly shown in Fig. 7. Rotatably mounted 55 on the member 13 is a sleeve 15 which is provided with four projections 8 which extend into the recessed portion of the pulley 12, and 16 are rollers between the projections 8 and which are arranged to lock the 60 pulley 12 to the member 13 when the rollers are moved along the cam surfaces on the end on the member 13. 14 are springs one end of each of which is connected to the sleeve 15, while the other ends thereof are connected to pins 17 extending outwardly from 65

the clutch member 13 and which pins extend through openings 18 in the sleeve 15. These springs tend to draw the roller 16 on the high portions of the cam when released by the escapement lever to lock the pulley 70 12 to the clutch member 13. 19 are projections on the periphery of the sleeve 15 and which projections are out of alignment with each other, for the purpose hereinafter described. Mounted in any desired manner on 75 the housing *y* on a pivot pin parallel with the shaft 11 is an escapement lever 20 having three arms, one of said arms being in the line of travel of one of the projections 19, while another of said arms is in line of 80 travel of the other projection 19, as clearly shown in Fig. 2. The third arm of the lever 20 is pivotally connected to the end of the core of a solenoid 21, the lower end of which core is pivotally connected to a lever 22 85 pivoted at 23. 24 is a projection on the lower face of the lever 22 which is adapted to rest on a roller 25 on the upper end of a lever 26 pivoted at 27, and connected to this lever 26 is the core of a solenoid 28. 29 is a 90 source of energy which is in circuit with the solenoids 21 and 28 and a main switch under the control of a switch arm *t*, and 31 is a hand switch in the circuit of the solenoid 28. One end of the switch lever *t* is also connected to the end of links *s* so that when either the hand lever *r* or lever *m* is shifted the switch will be thrown as hereinafter described.

The various parts of the machine as heretofore described are in their neutral position so that the belts *i* are running free as well as the pulley 12. When it is desired to start the machine in operation, the switch 31 is closed and the lever *r* is shifted, for instance, to the right, which will close the circuit through the solenoid 21 and the mechanism is so timed and connected that the table will move to the right and at which time it will complete what might be termed 100 the cutting movement. As soon as the dog *v* engages the lever *m*, the belts will be shifted to reverse the movement of the bed, and at the same time the switch *t* will be thrown to the right which will break the circuit to 105 the solenoid 21 and close the circuit to the solenoid 28. This energizing of the solenoid 28 will withdraw the lever 26 from under the projection 24 and permit the core of the solenoid 21 to drop by gravity. This dropping by gravity of the core of the solenoid 21 will throw the hooked arm of the lever 20 into contact with the periphery of the sleeve 15 and withdraw the other lever from under the first projection 19. This movement of the escapement lever will permit the springs 14 to become active and shift the rollers 16 to lock the pulley 12 to the clutch member 13 so that the shaft 11 will be rotated 180 degrees until the second projec- 110

tion 19 is engaged by the hooked member on the escapement lever 20, which will arrest the movement of the clutch member 15 and at which time the projections 8 will shift the 5 rollers 16 to disengage the clutch. This movement of the shaft 11 through the medium of gears 10 and 6 will rotate the disk 7 approximately 180 degrees and which will in turn through the action of the sector 10 2 actuate the pinion *w* to move the ratchet mechanism into a position to shift the tool at the next movement. The planer bed is now returned to move the work piece idly under the tool *u*, and at the end of this movement the dog 7 will again shift the lever *m*, which will again reverse the belts and shift the lever *t* which will first break the circuit to the solenoid 28 and close the circuit to the solenoid 21. This energizing of the solenoid 21 will shift the escapement 20 to the position shown in Fig. 2 which will again permit the shaft 11 to be rotated 180 degrees, and immediately after the lever 22 is raised by the core of the solenoid 21 the lever 26 will 25 drop into the position shown in Fig. 2 to prevent the lever 22 and the core of the solenoid 21 from dropping if the circuit to the solenoid 21 is broken before the table reaches the limit of its next movement which might 30 occur if the operator should stop the machine during a cut, as he would then break the circuit to the solenoid 21.

If the lock or latch were not provided, the feeding mechanism would be shifted as 35 soon as the circuit to the solenoid 21 was broken, which would throw the feeding mechanism out of timed relation.

If it is desired to cut out the automatic feed for any reason, it is only necessary to 40 open switch 31, to break the circuit to solenoid 28, and lock the escapement, and when the switch is again closed the automatic feed will be restored in proper relation to the table reciprocating mechanism.

45 The advantages of my invention result from the provision of an intermittently actuated tool feeding device in connection with an electrically actuated escapement to prevent the escapement from acting until after 50 the table has been moved to a predetermined point, to prevent the tool feeding mechanism from getting out of timed relation with the table reciprocating mechanism.

Having now fully described my invention, 55 what I claim and desire to protect by Letters Patent is:—

1. A metal working machine comprising means for reciprocating the cutting tool and the piece to be cut relative to each other, 60 means for reversing the motion at the end of each stroke, electrically controlled feeding mechanism for shifting the cutting tool at the end of each complete reciprocation, and means for preventing the electrically controlled feeding mechanism from getting

out of timed relation with the reciprocating means.

2. A metal cutting machine comprising means for reciprocating the cutting tool and the piece to be cut relative to each other, 70 means for reversing the motion at the end of each stroke, intermittently actuated feeding mechanism for shifting the cutting tool just prior to the beginning of each cut, and an electrically controlled device for preventing the feeding means from getting out of timed relation with the reciprocating means. 75

3. In a device of the character described, an intermittently actuated tool feeding mechanism, an escapement adapted to permit actuation of said feeding mechanism, and electrically operated means adapted to control the escapement. 80

4. In a device of the character described, an intermittently actuated feeding mechanism, an escapement, a lever therefor, electrical means for moving the escapement lever in one direction, means permitting the lever to move in the other direction, and an electrically actuated lock for the escapement. 90

5. A metal planer having a reciprocating table, means for reciprocating said table including reversing mechanism, intermittently actuated tool feeding mechanism, an escapement for controlling the feeding mechanism, 95 an escapement lever, a solenoid for actuating the escapement lever in one direction, said escapement lever being arranged to be moved in the other direction by gravity, an electrically controlled lock for preventing 100 the movement of the escapement under the force of gravity, and electrical switches controlled by the reversing mechanism for actuating the solenoid and the electrically controlled lock. 105

6. A planer having a moving table, means for reciprocating said table including reversing mechanism, a cutting tool, intermittently actuated mechanism for moving said tool at the beginning of each cutting stroke, 110 an escapement for controlling the intermittently actuated mechanism, an escapement lever, a solenoid for actuating said escapement lever in one direction, said escapement lever being arranged to be moved in the other direction by gravity, a switch for controlling the current to said solenoid, a lock for preventing the escapement lever from moving under the force of gravity, a solenoid for shifting said lock, a second switch for 120 closing the circuit through the lock solenoid, and means controlled by the reversing mechanism for actuating said switches. 115

7. A planer having a moving table, means for reciprocating said table including reversing mechanism, a cutting tool, intermittently actuated mechanism for moving said tool at the beginning of each cutting stroke, an escapement for controlling the intermittently actuated mechanism, an escapement lever, a 125

solenoid for actuating said escapement lever in one direction, said escapement lever being arranged to be moved in the other direction by gravity, a switch for controlling the current to said solenoid, a lock for preventing the escapement lever from moving under the force of gravity, a solenoid for shifting said lock, a second switch for closing the circuit

through the lock solenoid, means controlled by the reversing mechanism for actuating 10 said switches, and a third switch for controlling the circuit to the lock solenoid.

In testimony of which invention, I have hereunto set my hand, at Philadelphia, Pa., on this 16th day of June, 1920.

GEO. H. BENZON, JR.
